US0D1036156S

(12) **United States Design Patent** (10) **Patent No.:** **US D1,036,156 S**
(45) **Date of Patent:** **** Jul. 23, 2024**

(54) **PILLOW**

(71) Applicant: **Shenzhen Taineng Jikang Technology Co., Ltd**, Shenzhen (CN)

(72) Inventor: **Xia Zou**, Huizhou (CN)

(73) Assignee: **Shenzhen Taineng Jikang Technology Co., Ltd**, Shenzhen (CN)

(**) Term: **15 Years**

(21) Appl. No.: **29/863,751**

(22) Filed: **Dec. 22, 2022**

(30) **Foreign Application Priority Data**

Dec. 8, 2022 (CN) 202230824727.7

(51) **LOC (14) Cl.** **06-09**

(52) **U.S. Cl.**
USPC **D6/601**

(57) **CLAIM**

The ornamental design for a pillow, as shown and described.

DESCRIPTION

FIG. 1 is a front perspective view of a pillow, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof of its component one shown separated for ease of illustration; and,

(Continued)

FIG. 10 is a front perspective view thereof of its component two shown separated for ease of illustration.

1 Claim, 10 Drawing Sheets
